(57) **CLAIM**

The ornamental design for a trailer enclosure, as shown and described.

DESCRIPTION

FIG. 1 is a perspective view of the trailer enclosure showing my new design;

FIG. 2 is a left side elevation view thereof;

FIG. 3 is a front elevation view thereof;

FIG. 4 is a right side elevation view thereof;

FIG. 5 is a bottom plan view thereof;

FIG. 6 is a top plan view thereof;

FIG. 7 is a rear elevation view thereof; and,

FIG. 8 is a perspective view thereof, showing the design in use.

The broken lines in the drawings illustrate environment and forms no part of the claim.
